LIQUID-CONTROL SYSTEM.

1,137,390.

Specification of Letters Patent. Patented Apr. 27, 1915.

Application filed January 2, 1912. Serial No. 669,090.

To all whom it may concern:

Be it known that we, HERMAN W. FALK and WILLIAM K. ANDREW, citizens of the United States, residing at Milwaukee, in the 5 county of Milwaukee and State of Wisconsin, have invented a certain new and useful Improvement in Liquid-Control Systems, of which the following is a specification.

In view of the fact that our carbureter is 10 primarily designed to operate with such heavier fuels as kerosene, crude oil and the like, it is necessary that some means be provided for introducing into the carbureting chamber a relatively volatile fuel, as in order 15 that the engine may be started and in order that after it has been started it may operate, it may have to be heated up to that point at which the heavier, less volatile fuels may be economically used. With this end in 20 view, we have provided means for first supplying the reservoir and thus the carbureting chamber with gasoline and subsequently discontinuing the supply of gasoline and supplying it with kerosene.

25 Our invention therefore relates to improvements in carbureters and has for one object to provide means for feeding to the carbureter a plurality of different kinds of liquid fuels.

30 It is illustrated diagrammatically in the accompanying drawings, wherein—

Figure 1 is a plan view with parts removed; Fig. 2, a section along the line 2—2 of Fig. 1; Fig. 3, a section along the line 3—3 of Fig. 1; Fig. 4, a section along the line 4—4 of Fig. 1; Fig. 5, a section along the line 5—5 of Fig. 2; Fig. 6, a diagrammatic view.

Like parts are indicated by like letters 40 throughout the several figures.

The carbureter A contains the vacuum or carbureting chamber A¹ separated from the fuel reservoir A² by the partition wall A³ in which is mounted the needle valve A⁴ to 45 control the flow of combustible liquid from the reservoir to the carbureter.

The reservoir A² is provided on one side with the supply well B and the overflow well B¹ separated one from the other by the wall B² and from the remainder of the chamber A² by the wall B³. The chamber A² is provided with the substantially conical horizontally disposed partition wall B⁴ which divides the chamber into upper and lower 55 sections. The wall B⁴ is centrally perforate,

the perforation containing the removable collar B⁵ which surrounds the barrel of the needle valve A⁴. The passage B⁶ leads from the base of the supply well B through the wall B³ into the interior of the lower portion 60 of the receiver A² beneath the partition wall B⁴. The overflow well B¹ communicates with the upper portion of the reservoir above the partition wall B⁴.

The valve C which is rigidly attached to 65 the carbureter wall by the cap screw C¹ is provided with the supply and discharge pipes C², C³ communicating respectively through the ports C⁴, C⁵ with the wells B, B¹. The hollow conical valve C⁶ is rotatably 70 mounted in the conical valve seat C⁷ being held in position by the packing C⁸ and nut C⁹ and is adapted to be turned by means of the handle C¹⁰. The conical valve C⁶ is provided with the two radially disposed 75 passages C¹¹, C¹² leading from the hollow interior of the valve to the conical seat and being at right angles to each other, that is to say, separated by approximately ninety degrees. These passages which are located 80 in the plane of the passage C² are adapted at times to be in register with this passage which continues through to the valve seat C⁷.

The curved passage D in the wall of the 85 valve casing communicates at one end with the supply passage C² intermediate the carbureter and the conical valve C⁶ and at the other end with the vertically disposed gasoline supply pipe D¹. The passage D² communicates at one end with the interior of 90 the conical valve C⁶ and at the other end with the vertically disposed kerosene supply pipe D³. The curved passage D⁴ communicates at one end with the discharge passage C³ and at the other end with the conical 95 valve seat C⁷ in substantially the same plane as the passage C². The passage D⁵ communicates at one end with the passage D⁴ intermediate its two ends and at the other with the overflow pipe D⁶.

The valve casing is provided on its upper side with the semicircular plate E projecting from the shank E¹ in which is located the nut C⁹ and this plate is marked Kerosene, Gasolene and Stop as indicated in 105 order to aid the operator in positioning the valve for different operative conditions.

We have illustrated in connection with the fuel reservoir a water reservoir F substantially similar in construction to the fuel 110

reservoir, having the needle valve F^1 , the supply well F^2 and discharge well F^3 , communicating respectively with the supply pipe F^4 and discharge pipe F^5 .

5 We have indicated the carbureting chamber as being controlled at one end by the circular valve F^6 and discharging at the other end through the sleeve F^7 to the engine not shown. The reservoirs A^2 and F are 10 inclosed by the cover F^8 and provided with the port holes F^9 closed by the covers F^{10} held in position by the springs F^{11} about the shank of the needle valves.

15 The pump G which is diagrammatically shown is driven from the engine shaft G^1 and forces kerosene from a reservoir not shown through the kerosene supply pipe D^3 into the valve housing C , the overflow returning through pipe D^6 to the reservoir. 20 The hand pump G^2 is adapted to pump gasolene from the reservoir not shown through the gasolene pipe D^1 to the valve housing C . The valve G^3 is provided in the gasolene supply pipe D^1 to shut off the gasolene supply when it is necessary. 25

It will be evident that while we have shown in our drawings an operative device, still many changes might be made in size, shape and arrangement of parts without departing materially from the spirit of our invention, and we wish therefore that our drawings be regarded as in a sense diagrammatic.

30 The use and operation of our device are as follows: In operating our engine, when the engine is stopped the carburetor will be, by certain means subsequently to be described, drained of its fuel supply and therefore when it is desired to start the engine 35 the carburetor will be found free from any fuel whatever. The valve handle will be turned to the right until it co-incides with the letters Gas on the flat plate at the top of the valve. This will bring one of the ports 40 in the conical valve into register with the curved discharge passage in the valve housing and will at the same time shut off the supply passage from the interior of the conical valve. Gasolene will then be forced through 45 the gasolene supply passage, out through the curved supply passage, thence into the supply well, through this well, through the port at its bottom into the interior of the reservoir. The forcing will continue until 50 the gasolene completely fills the lower portion of the reservoir and is about to, or actually does overflow over the removable ring about the needle valve. The engine will then be started in the usual manner and 55 will use the gasolene in the supply reservoir. Meanwhile, kerosene will be fed by any suitable means, preferably responsive to the rotation of the engine, but here not shown, up to the interior of the conical valve. It will 60 then pass through the port therein, in reg-

ister with the discharge passage and return to the supply reservoir through this discharge passage. After the engine has been running and has been well heated up and the gasolene is about to be exhausted, the 70 valve will be rotated until the handle coincides with the letters Ker, thus bringing one of the ports in the valve into register with the supply pipe and shutting off the discharge pipe from the interior of the 75 valve. The fuel will then be pumped up through the conical valve, through the port into the discharge pipe and hence to the base of the supply well. It will pass through the port at the other side of this 80 base into the interior of the reservoir, filling the reservoir and overflowing over the overflow ring about the nozzle barrel. The overflow will then pass down into the discharge or overflow well and pass out through the 85 overflow passage into the overflow pipe. It will be noted that the supply well is open at the top and communicates with that portion of the reservoir which discharges into the overflow well, thus, in case of any stopping up of the lower portion of the reservoir the fuel will be able to escape back into the discharge. It will be noted also that by the arrangement shown, the lower portion of the fuel reservoir which is in communication with the carbureting chamber through the needle valve is kept constantly filled with the combustible liquid and since the liquid immediately overflows as soon as it reaches a height about that of the overflow ring, the 90 level of the liquid is always constant. In case it is desired to change the level of the fuel another ring may be substituted of different height. When the engine is stopped it is of course, necessary to drain the carbureting chamber and this is done by moving the valve into the stop position, thus bringing one of the ports in the valve into register with the supply and the other into register with the discharge, and since the supply communicates with the bottom of the reservoir, the liquid will drain from the bottom through the conical valve into the discharge. 95

100 We claim:

1. A liquid control system comprising a housing, a three-way valve contained therein, a liquid supply pipe leading to said housing and controlled by said valve, a liquid discharge pipe leading from said housing and controlled by said valve, a second pipe communicating with said housing and directly with said liquid discharge pipe independent of the valve, a run-off pipe leading from said housing and controlled by said valve and a liquid supply pipe leading to said housing and communicating with said run-off pipe independent of said valve. 115

2. The combination with a reservoir of a liquid supply and discharge system therefor 120

comprising a valve housing, a run-off pipe from the reservoir leading to and through the housing, a single supply pipe leading from the housing to the reservoir, a supply pipe leading to and through the housing and communicating directly with said single supply pipe and a valve control supply pipe leading to said housing and adapted to com-

municate with said single reservoir supply pipe or with the run-off pipe depending on the position of the valve.
